REFRIGERATING APPARATUS

Lawrence A. Philipp, Detroit, Mich., assignor to
 Kelvinator Corporation, Detroit, Mich., a corporation of Michigan

Application August 14, 1934, Serial No. 739,747

12 Claims. (Cl. 62—115)

The present invention relates to multiple refrigerating systems and particularly to systems of the type employing a plurality of evaporators which are connected to a common condensing mechanism.

One of the objects of the present invention is to provide an improved refrigerating system employing a plurality of evaporators in which one of the evaporators receives the liquid refrigerant from the other and in which the flow of refrigerant to the evaporators is controlled in accordance with the condition of the refrigerant in one of the evaporators.

A further object of the present invention is to provide a system of the above type in which the condition of the refrigerant in the evaporator last to receive liquid refrigerant is utilized for controlling the flow of liquid refrigerant to the evaporators.

Another object of the present invention is to provide an improved refrigerating system employing a plurality of evaporators of the type in which one evaporator is connected in series circuit relation with the other and in which each evaporator is provided with its individual suction line and to provide mechanism for preventing liquid refrigerant from entering the condensing mechanism through one of the suction lines and to control the quantity of liquid refrigerant delivered to the evaporators in accordance with the condition of the refrigerant in the outlet of the other evaporator.

A still further object of the present invention is to provide a refrigerating system employing two evaporators, a valve between these evaporators, for causing a differential in temperatures and in order to prevent an excessive quantity of liquid refrigerant in the evaporator first to receive liquid refrigerant, to provide a by-passing means around the interposed valve which is operated in response to an excessive quantity of refrigerant in the evaporator first to receive liquid refrigerant.

The invention itself, however, both as to its organization and its method of operation, together with additional objects and advantages thereof, will best be understood from the following description of specific embodiments, when read in conjunction with the accompanying drawings, in which:

Fig. 1 is a schematic view diagrammatically representing a two temperature refrigerating system arranged in accordance with my invention; and

Fig. 2 is a similar view showing a second embodiment of my invention.

Referring more particularly to Fig. 1 of the drawings, the apparatus comprises a high temperature refrigerating coil 1 and a low temperature coil 2 which are so connected into a refrigerating system that they are maintained at different temperatures by a liquid refrigerant which is supplied from condensing means comprising a double suction pressure compressor 3 and a condenser 4. The refrigerant passing from the compressor through the condenser 4 gives up its latent heat of vaporization and passes as a liquid through a feed line 5 to a liquid receiver 6 and thence to a needle valve 7 which controls its admission to the system, in a manner to be subsequently set forth.

The refrigerant passes from the needle valve 7 through a conduit 8 to the high temperature coil 1 and thence into a float valve chamber 11. The liquid refrigerant passes through the float valve chamber 11 and thence by conduit means 12 to a weighted pressure reducing valve 13, from the outlet of which the refrigerant passes through a conduit 14 to the low temperature coils 2. The refrigerant while passing through the high temperature coils 1 is maintained at a higher pressure than in the lower temperature coils by the weighted pressure reducing valve 13 interposed therebetween. Consequently the refrigerant in the low temperature coils 2 vaporizes at a lower pressure to maintain a lower degree of temperature than in the high temperature coils 1. It will be understood that both of the cooling coils may be provided with heat conductive fins 9 to increase their heat absorbing capacity and they may be enclosed in suitable heat insulating compartments 10 as indicated by dotted lines.

From the low temperature coils 2 the refrigerant vapor passes through a conduit 16 into a housing 17 which encloses a cup shaped float member 18 for actuating the needle valve 7 to control the admission of liquid refrigerant to the system through the high temperature coil 1. The needle valve float housing 17 is connected to the low pressure side of the high suction cylinder 21 of the compressor by means of a conduit 22 connected through the needle valve cover 23 to a pipe 24 the lower open end of which extends downwardly from the cover 23 into the cup 18 adjacent the bottom thereof.

From the top of the float valve chamber 11 a medium pressure suction line 27 is connected to the low pressure side of the second cylinder 28 of the compressor. The outlet of the float valve is connected through a by-passing conduit 31 to the line 14 between the pressure reducing valve and the low temperature coil. This serves to discharge the liquid refrigerant from the float valve chamber 11 around the pressure reducing device 13 whenever it exceeds a predetermined level in the float valve chamber thus preventing the passage of liquid refrigerant into the medium suction line 27.

The needle valve 7 is enclosed in a valve chamber 37 which is supported from the valve

cover 23 and it is actuated to regulate the admission of liquid refrigerant by a valve lever 36 which is pivotally joined at one end to the valve needle 7 and has its other end projecting from the needle valve chamber 37 through a lateral extension 38 thereon.

The valve lever 36 is pivoted on a pivot pin 39 which extends through the valve chamber extension 38. The extended portion of the lever 36 passes through the head 42 of a tilting flexible metal bellows 43 to which it is hermetically sealed. The edges of the flexible bellows 42 are secured to the outer edges of the valve chamber extension 38 in hermetically sealed relation whereby the valve lever 36 may be tilted to actuate the valve 7 within the chamber 37 while maintaining hermetically sealed relation.

The cup shaped float member 18 within the valve housing is preferably of light gauge sheet metal and it functions as a float as it is buoyed up by the liquid refrigerant entering the housing 17. In order to actuate the valve lever 36, in accordance with the movements of the cup float 18, a float lever 45 is pivotally connected thereto by a pivot pin 46 which extends across the open end of the cup 18. The other end of the float lever 45 is connected through a link 47 to the free end of the valve lever 36. In order that the vertical movements of the cup 18 may actuate the float lever 45 the latter is pivoted in an intermediate point upon a pivot pin 48 which is rigidly mounted in a bracket 49 depending downwardly from the valve cover 23 which covers the valve housing 17.

It will be apparent that liquid refrigerant entering the needle valve housing 17 will cause the cup shaped float 18 to rise thereby rotating both the float lever 45 and the valve lever 36 clockwise, thus lifting the valve needle 7 to engage its seat and restrict the admission of liquid refrigerant to the system. Lubricating oil in the system being lighter than the refrigerant bubbles over the edge of the cup float 18 without actuating it to close the needle valve. As the oil enters the cup 18 it is drawn up the suction pipe 24 and returns to the compressor which may be provided with an oil drain 50 in the intake manifold for draining the oil into the crank case. During the operation of the system if the liquid refrigerant in the system becomes excessive, the needle valve 7 will be immediately closed to restrict the admission of refrigerant to the system until the liquid refrigerant therein has time to vaporize.

The cylinders of the double suction pressure compressor are relatively so designed that a suitable suction pressure is maintained in the high suction line and the medium suction line. The temperature differential maintained between the high temperature and the low temperature coils by the weighted pressure reducing valve 13, is preferably selected or adjusted in accordance with the desired operating characteristics, and the compound compressor is preferably driven by an electric motor 54 which may be controlled automatically by means of a switch 55 actuated by a thermostatic device 56 associated with one of the coils. It will be understood that the motor switch may be actuated by a pressure responsive device associated with a suitable portion of the system or the motor may run continuously if desired.

In Fig. 2 I have shown a second embodiment 75 of my multiple-temperature multiple-suction re-

frigerating system which is simplified somewhat by eliminating the float valve and chamber from the system. The various elements of the system which are similar to the corresponding elements discussed with reference to Fig. 1 are designated by similar reference characters. 5

In the simplified embodiment of my system the medium suction line 27 from the second cylinder 28 of the compressor is connected through a vertical cylinder 61 thence by way of a conduit 10 62 to a line 63 which extends directly between the high temperature coil 1 and the weighted pressure reducing valve 13. The feed line 5 for supplying the system with liquid refrigerant from the condenser 4 extends through a pipe 64 15 which is coiled in close coupled heat exchange relation around the vertical cylinder 61 and thence extends to the needle valve 7.

In operation the liquid refrigerant which rises 20 into the cylinder 61 in the medium suction line is heated by the liquid refrigerant which passes from the condenser in intimate heat exchange relation therewith. This vaporizes any liquid refrigerant rising in the medium pressure suction line 27 and prevents the liquid entering the 25 compressor where it would cause knocking and eventually fracture the cylinder walls. Although I have disclosed my invention as specifically applied to a two temperature system it will be readily understood that the features of 30 my invention are applicable to various systems in a manner which will be readily understood by those skilled in the art.

While it is necessary for the purpose of illustration to describe the several disclosed forms 35 of my invention in detail, it will be apparent that the invention is not so limited, and that other forms and applications thereof, are embraced within the scope of the appended claims.

I claim as my invention—

1. A refrigerating system comprising in combination a plurality of evaporators, means for withdrawing gaseous refrigerant from the evaporators condensing the same and conducting the condensed refrigerant to the evaporators, one 45 of said evaporators being connected in series circuit relation with the other for receiving liquid refrigerant from the said other evaporator, each of said evaporators having a suction line connected with the first mentioned means, pressure responsive means responsive to the difference in pressures between said evaporators for causing refrigerant to be fed from said other evaporator to said one evaporator, means responsive to excess refrigerant from said other evaporator for by-passing the excess refrigerant around said pressure responsive means, for preventing liquid refrigerant from being conducted from the said other evaporator to the first mentioned means, a valve for controlling the flow 50 of refrigerant from the first mentioned means to said evaporator, and means responsive to the condition at the outlet of said one evaporator for controlling said valve. 55

2. A refrigerating system comprising in combination a low temperature evaporator and a high temperature evaporator said low temperature evaporator being adapted to receive liquid refrigerant from the high temperature evaporator, a valve interposed between said evaporators, a suction line for each of said evaporators, means for withdrawing gaseous refrigerant from 70 said evaporators and cooperating with said valve for maintaining different pressures in said evaporators, and a heat exchanger for applying heat 75

from a portion of the system to vaporize the excess of liquid refrigerant which is discharged from the outlet of said high temperature evaporator for preventing the conduction of liquid refrigerant from the high temperature evaporator to said withdrawing means.

3. A refrigerating system comprising in combination a low temperature evaporator and a high temperature evaporator said low temperature evaporator being adapted to receive liquid refrigerant from the high temperature evaporator, a valve interposed between said evaporators, a suction line for each of said evaporators, means for withdrawing gaseous refrigerant from 15 said evaporators, and cooperating with said valve for maintaining different pressures in said evaporators, and means responsive to excess refrigerant from said high temperature evaporator for bypassing the excess refrigerant around said 20 valve, for preventing the conduction of liquid refrigerant from the high temperature evaporator to said withdrawing means.

4. A refrigerating system comprising in combination a low temperature evaporator and a high temperature evaporator said low temperature evaporator being adapted to receive liquid refrigerant from the high temperature evaporator, a valve interposed between said evaporators, means for withdrawing gaseous refrigerant from 10 said evaporators, and cooperating with said valve for maintaining different pressures in said evaporators, a heat exchanger for applying heat from a portion of the system to vaporize the excess liquid refrigerant from the outlet of said 5 high temperature evaporator, for preventing the conduction of liquid refrigerant from the high temperature evaporator to said withdrawing means, and means responsive to the condition of refrigerant at the outlet of the low temperature evaporator for controlling the flow of liquid refrigerant to the high pressure evaporator.

5. A refrigerating system comprising in combination a low temperature evaporator and a high temperature evaporator, said low temperature evaporator being adapted to receive liquid refrigerant from the high temperature evaporator, a valve interposed between said evaporators, a suction line for each of said evaporators, means for withdrawing gaseous refrigerant from 10 said evaporators, and cooperating with said valve for maintaining different pressures in said evaporators, means responsive to excess refrigerant from said high temperature evaporator for bypassing the excess refrigerant around said valve, for preventing the conduction of liquid refrigerant from the high temperature evaporator to said withdrawing means, and means responsive to the condition of refrigerant at the outlet of the low temperature evaporator for controlling the flow of liquid refrigerant to the high pressure evaporator.

6. In a multiple temperature refrigerating system the combination of a high temperature coil, a low temperature coil, refrigerant condensing means, a liquid refrigerant feed line extending from said condensing means to said high temperature coil, a valve interposed in said feed line, pressure reducing means interconnected between said coils, a high suction line extending from said low temperature coil to said condensing means, means responsive to liquid in said suc-

tion line for closing the valve in said feed line, a medium suction line, means interconnecting said medium suction line between said high temperature coil and said pressure reducing means comprising a heat exchange device, and a second portion of said heat exchange device comprising conduit means connected in series in said feed line.

7. A refrigerating system comprising the combination of a plurality of refrigerant evaporators, a refrigerant compressor, conduit means operatively connecting said evaporators in series relation with said compressor, means responsive to pressure only for controlling the flow of refrigerant between said evaporators, means responsive to liquid refrigerant only, and conduit means connecting said pressure responsive and liquid means in bypassing relation.

8. A refrigerating system comprising the combination of a plurality of refrigerant evaporators, a refrigerant compressor, conduit means operatively connecting said evaporators in series relation with said compressor, means responsive to pressure only for controlling the flow of refrigerant between said evaporators, a float valve, conduit means connecting said float valve in bypassing relation around said means, and a suction conduit connected between the float chamber of 20 said float valve and said compressor.

9. A refrigerating system comprising the combination of a plurality of refrigerant evaporators, a refrigerant compressor, conduit means operatively connecting said evaporators in series relation with said compressor, means responsive to pressure only for controlling the flow of refrigerant between said evaporators, a float valve, conduit means connecting said float valve in bypassing relation around said means, a suction conduit connected between the float chamber of 25 said float valve and said compressor, and means responsive to liquid refrigerant from the outlet 30 of the last evaporator for shutting off the supply of refrigerant to the first evaporator.

10. A refrigerating system comprising, in combination, a plurality of liquid refrigerant evaporators connected in series, pressure differential means between said evaporators for controlling the flow of liquid and gaseous refrigerant from one evaporator to another, and means for bypassing refrigerant from one evaporator to the 45 other around said pressure difference means.

11. A refrigerating system, comprising in combination, a plurality of liquid refrigerant evaporators, means connecting said evaporators responsive to the pressure in one of said evaporators to control the flow of liquid and gaseous refrigerant to another evaporator, and means for bypassing refrigerant from one evaporator to the other around said means.

12. A refrigerating system comprising, in combination, a plurality of liquid refrigerant evaporators, a pressure difference device interconnecting said evaporators for controlling the flow of liquid and gaseous refrigerant from the first to a second evaporator, valve means associated 55 with the outlet of the second evaporator for controlling the admission of liquid refrigerant to the first evaporator, and means for bypassing refrigerant around said pressure difference device.
